UNITED STATES PATENT OFFICE

RUFUS B. RAWLINS, OF EL PASO, TEXAS

DESIGN FOR A BOOTH

Application filed June 24, 1929. Serial No. 31,810. Term of patent 14 years.

To all whom it may concern:

Be it known that I, RUFUS B. RAWLINS, a citizen of the United States of America, residing at El Paso, in the county of El Paso and State of Texas, have invented a new, original, and ornamental Design for a Booth, of which the following is a specification, reference being had to the accompanying drawings, forming a part thereof.

Figure 1 is a perspective view of the booth showing my new design.

Figure 2 is a top plan view thereof.

I claim:

In Figure 1 only one side of the booth is visible but it is to be understood that the other side is identical in design.

The ornamental design for a booth as shown and described.

RUFUS B. RAWLINS.
